UNITED STATES PATENT OFFICE.

GEORGE H. WINSLOW, OF SOUTH HADLEY FALLS, MASSACHUSETTS, ASSIGNOR OF ONE-HALF TO FRANK S. GORDON, OF BONDSTVILLE, MASSACHUSETTS.

METHOD OF PRINTING WARP.

1,181,627.

Specification of Letters Patent.

Patented May 2, 1916.

Application filed January 2, 1914. Serial No. 810,008.

To all whom it may concern:

Be it known that I, GEORGE H. WINSLOW, a citizen of the United States of America, residing at South Hadley Falls, in the county of Hampshire and State of Massachusetts, have invented a new and useful Method of Printing Warp, of which the following is a specification.

My invention relates to improvements in methods of printing warp for use in the manufacture of cloth or fabric of different kinds and grades, and consists in general and essentially in treating the warp-units to cause them to adhere to each other laterally so as to form a flat sheet, strip or web, in completely drying such web on one side while leaving the other side moist, in printing, on or, applying the color to the dry side of such web, and in setting the color, all as hereinafter set forth. Since one side of the warp is moist at the time the color is applied to the dry side, said color strikes into said warp and comes through on the other or moist side.

In the past many unsuccessful attempts have been made to produce a printed warp which, when woven into cloth, discloses or presents the identical pattern on both sides of the fabric, it having been necessary not only to have recourse to a number of disconnected, and it might almost be said unrelated, operations, separated by considerable intervals of time, but to employ a variety of different and independent machines, for producing even the imperfect product heretofore brought forth. The several operations involved in previous methods included sizing the warp, drawing-in, placing the warp in a loom to weave threads across it at certain intervals for the purpose of retaining the warp-units in place for printing, removing the warp from such loom and printing, again drawing-in, and placing said warp in said loom the second time for weaving, at which time or during the weaving operation the threads that were first woven in having to be taken out as they are reached, which caused imperfect or defective places to appear in the cloth, and a loss of production by the stopping of the loom for this purpose.

With my method, whereby or wherein the warp is completely dried on the side to be printed, between the sizing and printing steps, next dried, then alternately steamed

and dried, and finally thoroughly dried and made ready to wind on the loom-beam, all in one run or by a series of correlated, naturally sequential, and continuous steps, I overcome the serious objections pointed out above and consequently very materially decrease the cost of production, increase the product, and produce a warp with which a perfect fabric can be manufactured, and this is the primary object of my invention.

By partially drying the warp so that one side is completely dry, after said warp has been treated with size or gum to cause the warp-units to adhere to each other and before said warp has the pattern printed thereon, a suitable printing surface is obtained and said warp is prepared to take the color in such a manner as to produce said pattern on both sides alike, and if a warp-unit rolls during the subsequent weaving process no break is produced in the pattern. This is a most important and valuable feature of my invention, and in connection therewith it should be observed that, inasmuch as the warp receives the color on the dry side, such side comes next to the color-applying member and does not have a tendency to adhere to the same, by reason of the adhesive material in said warp, or to deposit such material on such member. It is practically impossible to apply color evenly, sharply, and successfully directly to a moist surface, because in such case the color will run and spread laterally, instead of producing a clear-cut surface pattern and striking through to produce such pattern throughout the warp and on the other side, as is done when the side to which the color is directly applied is dry and the other side moist at the time of printing. Thus it is seen that, by completely drying the side of the warp to be printed, I remove all danger of spoiling the pattern on the printed side and therefore on both sides and throughout the warp. By this method the color in the warp is set therein so that it will not run or "bleed" in finishing the woven fabric. This obviates the necessity of steaming the cloth after it is woven.

It is to be understood that the term "color" is herein used in its broad sense, and signifies any single color or shade or any combination of colors or shades or both.

Other objects and advantages will appear in the course of the following description.

I attain the objects and secure the advantages of my invention in the manner herein set forth, and by means such as those illustrated in the accompanying drawings, in 5 which—

Figures 1, 1^a and 1^b together constitute a side elevation of a machine which may be practically and profitably employed in carrying out my method.

10 Similar figures refer to similar parts throughout the several views.

In Fig. 1, the side of the steam-box, which is next to the beholder, is omitted to disclose the interior of such box and its 15 contents, and one of the cylinder connections is shown in section, thus bringing clearly into view the steam passage in and through such connection. In Fig. 1^a, a part of the size-box is broken out to show the 20 guide-roll which takes the warp down into the size.

The directions of moving parts and members are indicated on the drawings by arrows.

25 Although I have shown and will describe a practicable and efficient machine to aid in giving effect to my method, I do not thereby restrict the method or its application and use in any way.

30 I will first describe the method in detail and will then explain the machine, illustrated in the accompanying drawings, and the manner in which the method is carried out with the aid of such machine.

35 The first step in the method consists in applying adhesive material to a series of warp-units, which units have been properly arranged side by side in readiness for printing. The warp-units are usually conducted 40 from a series of section-beams, through one or more reeds, to and through a size-box and its rolls, for the purpose of arranging such units in proper formation and applying the adhesive material thereto. The

45 warp-units are now saturated with the adhesive material, such as a size or gum which is prepared for this particular purpose, and said units adhere to each other laterally so that they form a practically unbroken strip 50 or web, and this web is next completely dried on one side, preferably by being carried over or brought into contact with a cylinder which is heated to the proper temperature to produce the partial drying effect desired, that is, partially with reference to the web as a whole. This is the second step in the method. As the third step in the method, the warp, which is now 55 dry on one side and moist on the other, has

60 applied to the dry side color wherewith the printing or pattern is produced, such pattern being even, sharp, and uniform by reason of the fact that the side to which it is applied is dry, as previously observed.

65 Owing to the fact that the warp is dry on

the side only which receives the color, said color strikes through or penetrates the moist portions of said warp and appears on the side opposite to that where it is applied. Thus the warp is colored or printed alike 70 throughout. The printed warp is now dried as another step in the process, such drying usually being effected through the medium of one or more drying cylinders. After being thus dried the warp is alternately 75 steamed and dried or partially dried to fix or set the color, the drying and steaming alternating on the opposite sides of said warp, after an initial steaming and followed at the end by a final steaming. This 80 is an important step and may be carried out with the aid of a steam-box and a series of steam-heated cylinders in said box. Following and supplementing the last-mentioned step is a final drying of the warp, 85 which may be brought about by means of a heated cylinder. Although the final drying might be considered as the last step in the method, the method may be extended to include measuring the number of yards and the length of the cuts or pieces therein, separating the warp-units so that they can be used for weaving, and winding such units on a loom-beam. While this constitutes the 90 method in detail, it is apparent that some departure therefrom may be made without violating the spirit of my invention.

Passing now to the machine, it may be somewhat briefly described as follows:—

Situated approximately in the center of 100 the machine lengthwise is a printing-mechanism frame 1. Supported by one side of the frame 1 is one end of a shaft 2, the bearing for the other end of said shaft not being shown. Mounted on the shaft 2 are 105 a pulley 3, a sprocket-wheel 4, and a pinion 5. Power from any suitable source is applied to the pulley 3, and it is from this point that the entire machine is driven. Power is transmitted to all parts of the 110 machine, except to the printing mechanism which is driven by the pinion 5, through the medium of the sprocket-wheel 4, a sprocket-chain 6, a series of sprocket-wheels 7, countershafts 8, sprocket-chains 9, and other driving members hereinafter more 115 particularly pointed out. There are five countershafts 8, and the middle one is that driven by the sprocket-chain 6 and which in turn drives the other four. All driving and driven parts are so timed that at no place does any undue strain come upon the warp.

The numeral 10 designates the warp.

A hanging bearing 11 is provided for 120 each end of each countershaft 8, such bearing being secured to the upper framework of the machine, which is represented at 12.

Depending from the frame-work 12, near the front end thereof and on each side, is a 130

- 5 bracket 13, the rear end of the horizontal arm of such bracket being attached to a steam-box 14. Back of each bracket 13 and in the rear of the transverse center of the machine is a U-shaped bracket 15, that depends from the framework 12 and has a horizontal cross-piece 16 near the top. At the rear of the machine on each side are two uprights 17 and 18.
- 10 Journaled in a bearing 19, on the front of each bracket 13, is a hollow trunnion 20 of a steam-heated cylinder 21. This cylinder is associated with the steam-box 14 and a series of cylinders 22 therein. Having its 15 shaft 23 journaled at each end in a bearing on the bottom member of each bracket 13 is a guide roll 24. Journaled in a bearing 25, on the front of each bracket 15, is a hollow trunnion 26 of a steam-heated cylinder 27, and in a similar bearing, on the rear of 20 said bracket, is a hollow trunnion 28 of a steam-heated cylinder 29. The cylinders 21, 22, 27 and 29 are for drying purposes, and the last-mentioned cylinder is that which 25 partially dries the warp as the latter passes over it, instead of effecting the complete drying of a moving element as do the cylinders 21 and 27, for which reason said cylinder 29 is termed the half-drying cylinder.
- 30 A guide roll 30 has its shaft 31 journaled at each end in a bearing on the bottom member of each bracket 15, and a guide roll 32 has its shaft 33 journaled at each end in a bearing on each member 16. On the back of 35 each bracket 15 are bearings for the shafts 34 and 35, at each end, of a guide roll 36 and a guide roll 37, respectively. A bearing on the back of each upright 17 supports one end of the shaft 38 of a guide roll 39, 40 and a similar bearing on the back of each upright 18 supports one end of the shaft 40 of a guide roll 41.
- 45 A system of steam pipes is provided to heat the several drying cylinders and other parts of the machine where heat is required and for supplying free steam where it is needed, and the live-steam pipes of such system are designated by the numeral 42, and the exhaust-steam pipes by the numeral 43. Steam from any suitable source of supply is introduced at 44, Fig. 2^a, into the live-steam pipes 42, and the exhaust steam escapes from the pipes 43 at the point 45, in said view, or is led away through pipes 55 (not shown) from such point. The pipes 42 are supplied wherever necessary with valves 46, and safety-valves 47 are provided at such points as may be necessary or desirable. Live steam enters the half-drying 60 cylinder 29 at 48, it enters the cylinder 27 at 49, and the cylinder 21 at 50. The exhaust steam escapes from the aforesaid cylinders at the end of each which is opposite to that where the live steam enters.
- 65 Within the steam-box 14 is a pair of
- stand-pipes, one of which appears at 51 in Fig. 1. Live steam enters the standpipe 51, which is shown, at 52, and exhausts through the stand-pipe on the other side at the point indicated at 53. Live steam enters the 70 steam-box 14 at 54, and exhausts through a pipe 55 at the top of said box. On the front and back of each stand-pipe 51 is a series of brackets 56 for the support of the hollow trunnions 57 at the corresponding 75 ends of the cylinders 22. Each bracket 56 has a passage 58 therein which opens at one end into the stand-pipe 51, to which said bracket is attached, and at the other end into the open terminal of the trunnion 57 80 journaled in such bracket.
- 85 Live steam entering the right-hand stand-pipe 51 at 52, rises in said pipe, passes through the passages 58 in the several brackets 56 attached to said pipe and enters the cylinders 22 through their trunnions 57 into which said passages open. From the cylinders 22 the steam escapes through the trunnions and the passages in the brackets at the opposite ends of said cylinders into 90 the stand-pipe on the opposite or left-hand side, and escapes from said last-mentioned stand-pipe at 53. In this manner and by this means the cylinders 22 are heated to the necessary degree of temperature. 95
- 100 Each of the cylinders 22 is provided at one end with a gear 59. Two of the gears 59 on the front are driven in opposite directions by a pinion 60 which is secured to a shaft 61 that is journaled in the steam-box 14. Secured also to the shaft 61 is a sprocket-wheel 62, and a sprocket-chain 63 drives said sprocket-wheel from one of the sprocket-wheels 7 on the second counter-shaft 8, the countershaft 8 at the front end 105 of the machine being considered as the first. The upper gear 59 which is in mesh with the pinion 60, is also in mesh with the two upper gears 59 and so drives them both in the direction opposite to that in which said 110 first-mentioned gear is driven by said pinion. The remaining gears 59 in the train are in mesh one with another on opposite sides of the vertical plane between the axes of the stand-pipes 51, so that each gear below 115 and on the opposite side relative to the next adjacent gear above is driven by the latter in the opposite direction thereto, commencing with the second front gear from the top, which is driven by the second rear gear 120 from the top. By this arrangement is maintained or secured the feed for the warp 10 in the steam-box 14, which said warp enters at 64 and passes directly to the lower-most cylinder 22, then takes a serpentine course over and under or partially around the cylinders 22, and finally after passing over the uppermost cylinder leaves said box 125 at 65.
- 130 The printing mechanism consists in part

of a felt-covered cylinder 66 which is mounted on a shaft 67 that is journaled at each end in a bearing-block 68 arranged to slide vertically in a slot 69 in each side of the frame 1. A backing-cloth, or the gray as it is called, 70, is required to prevent the warp 10 from coming into direct contact with the felt surface of the cylinder 66. The gray 70, starting from a roller 71 at 5 the back end of the machine, upon which said gray is wound, passes upwardly, through a series of tension bars 72 fastened to the rear sides of the uprights 17, to and over the guide roll 39, then forwardly to and 10 over the guide roll 37 and downwardly under and over two spreading bars 73 fastened beneath the brackets 15, thence under the cylinder 66 and up and over the drying cylinder 27 to a guide roll 74, next upwardly 15 and rearwardly past the guide roll 30 and in contact therewith and over the guide roll 36 to the guide roll 41, and finally downward through a series of tension bars 75 to be wound on a roller 76. The roller 71 has a 20 shaft which is journaled at each end in a bearing 77 on the back side of the corresponding upright 17. The tension bars 75 are fastened to the uprights 18. The guide roll 74 has a shaft 78 journaled at each end 25 in a bearing 79 located at the lower front corner of each bracket 15. A bar 80, having each end attached to one of the uprights 17, assists in supporting the gray on its return.

30 A rewinding apparatus or mechanism is provided for the gray 70, and such mechanism comprises a frame 81 having mounted therein a friction roller 82, a holding bar 83 at each end, and a latch 84 also at each end, 35 together with means for driving said roller. The roller 82 is mounted on a shaft 85 which is journaled in the frame 81. Each bar 83 is pivoted at 86 to the contiguous end of the frame 81, and each latch 84 is pivoted at 87 40 to such end of said frame. The parts form a vertical slot 88 in each end of the frame 81 in which is received the protruding terminal of a shaft 89 on which the roller 76 is mounted. The roller 76 and the convolutions 45 of the gray 70 thereon rest on the roller 82, and as said roller 82 is rotated the members above are also rotated to wind up said gray after it has passed through the printing mechanism and so served its purpose. The roller 82 is driven in the proper 50 direction to rewind the gray by means of a pulley 90 secured to the shaft 85, a pulley 91 secured to the rearmost countershaft 8, and a crossed belt 92 which connects said pulleys. As the size of the roll above the 55 roller 82 increases the shaft 89 moves upwardly in the slots prepared for it. The aforesaid roll can be removed by releasing the holding bars 83 from the latches 84.

60 In passing around the drying cylinder 27

the gray 70 is dried so that it will not mildew after being wound on the roller 76. The dampness which the gray receives and which is removed by the cylinder 27 comes from the color applied to the warp during 70 the act of printing. Next in order forward of the gray-handling apparatus is a rack 93 for a series of section-beams 94 from which the warp 10 starts. The section-beams 94 have shafts or trunnions 95 which 75 are journaled in suitable bearings on the frame 93, and each of such beams is provided with a weight 96 and a rope 97 to form what is commonly known as a drag-rope tension.

At 80 are shown a plurality of guide rods for the warp-units from certain of the section-beams.

In front of the section-beams 94 is a leasing-reed 99, and next in order, when the 85 same is required, is an adjusting reed 100. The reeds 99 and 100 are supported on a pair of rods 101 that extend rearwardly from a size-box 102. Each rod 101 is supported at the rear end by an upright 103. 90 The leasing reed 99 is of ordinary construction, and the objects of the same are to retain the warp-units in position for printing, and for making the weaver's lease on the loom-beam. The adjusting reed 100 is 95 for the purpose of accurately guiding the warp-units when stripes are to be printed thereon. This reed is necessarily adjustable, as will be readily understood.

The size-box 102 is provided at the rear 100 with a guide roll 104 and in front of this with a guide roll 105, also with a guide roll 106 inside and below the surface of the size or gum which said box contains, and with a pair of under squeeze-rolls 107 and a pair 105 of upper squeeze-rolls 108. The squeeze-rolls 107 are mounted on shafts 109 which are journaled in the sides of the size-box 102, and the squeeze-rolls 108 are mounted on shafts 110 which are received in slots in 110 the upper edges of said sides. Steam enters the size-box at 180.

The warp 10 passes forward from the section-beams 94 to and through the leasing-reed 99, and to and through the adjusting 115 reed 100 if present, over the guide rolls 104 and 105, down under the guide-roll 106, and upwardly and forwardly between the rear squeeze-rolls 107 and 108 and the front squeeze-rolls 107 and 108. The warp is saturated with the size when it passes under the roll 106, and the surplus size is squeezed out of said warp by the rolls 107 and 108. It is here that the first step in the method occurs. The squeeze-rolls 107 are driven by 120 means of gears 111 on the shaft 109, an intermediate gear 112 mounted on a stud 113 projecting from the size-box 102, said intermediate gear being in mesh with said first-mentioned gears, a gear 114 on a shaft 115 125

- which is journaled beneath said box, said gear 114 being in mesh with said gear 112, a sprocket-wheel 116 on said shaft 115, a sprocket-chain 117, and a sprocket-wheel 118 on the fourth counter-shaft 8. As the squeeze-rolls 107 are driven, by means of the mechanism provided for that purpose, the squeeze-rolls 108 are actuated and the warp 10 is drawn through the size-box and the adhesive material therein. The warp passes out of the size-box over the front of the forward squeeze-roll 108, and is then in a thoroughly sized condition, with the warp-units adhering to each other.
- 15 It may be remarked in passing that, in order to prepare the warp for printing and for weaving after it is printed, it is necessary to apply thereto adhesive material of a suitable character. Without properly sizing the warp it would be quite impracticable if not impossible successfully to apply color thereto.
- 20 From the size-box 102 the warp 10 passes upwardly and rearwardly to the half-drying cylinder 29, over the same and downwardly and forwardly to the cylinder 66. The heat of the cylinder 29 is so regulated that in passing over said cylinder the warp is dried only on the side which comes in contact 25 with said cylinder, while the other side of said warp is left in a damp condition. Here occurs the second step in the method, and it is by reason of this step or as a result of the same that the warp is so prepared as to 30 make it possible for the color, which is subsequently applied to the dry side of said warp, to produce the desired effect on said side and strike through and thoroughly penetrate and permeate the warp-units, 35 with the result that the pattern printed thereon shows alike on both sides of the cloth woven with said units as the warp thereof. Besides this very important feature or result, which emanates from the presence of 40 the half-drying cylinder and the step in the method which said cylinder is instrumental in inducing, there is the other advantage hereinbefore noted, which is that the size on the side of the warp that comes next to the printing-roll or -rolls is dry, hence does 45 not stick to such roll or rolls.
- 45 There is involved in the third step in the method the printing mechanism of the machine, and this mechanism comprises, with the frame 1 and the cylinder 66, a printing-roll 119, a doctor 120 for such roll, a color-box 121 having a furnisher-roll 122 therein, and driving mechanism. The color-box 121 is supported within the frame 1, and the 50 furnisher-roll 122 is in contact with the engraved roll 119 above. The furnisher-roll 122 is mounted on a shaft 200 journaled in the box 121, and said shaft is driven by a gear 201 thereon and a gear 202 on the engraved-roll shaft 131. The furnisher-roll 55 transfers the color in the box 121 from such box to the engraved roll 119 and keeps the latter filled or supplied. There may be more than one printing or engraved roll. The doctor 120 is mounted on a rod 125 which is journaled in the frame 1 behind the printing-roll 119, said doctor serving the usual purpose of such a device. A vertical screw 126 is tapped into and through a cap 127, on each side of the frame 1, to bear on the block 68 in the slot 69 under said cap. Means is provided for elevating the shaft 67 and the cylinder 66, when it is necessary to do so and the screws 126 are turned up. Said means comprises a lever 128 mounted at 129 on the frame 1, and other parts which need not be described here.
- 60 The printing-roll 119 is driven by means of a gear 130, on the shaft 131 upon which said roll is mounted and which shaft is supported as is customary upon weighted levers, one of which is represented at 124 mounted on a rod 123, in Fig. 1^a, an intermediate gear 132 carried on a stud 133 which projects from said frame, and the gear 5. The gears 130 and 202 are on opposite terminals of the shaft 131. The cylinder 66 is actuated by the gray 70 and the warp 10 and the frictional contact of the parts with the printing-roll. The cylinder 27 is actuated by the gray and warp, and the latter alone rotates the cylinder 29. The printing-roll 119 and the cylinder 66 revolve, of course, in opposite directions. The gray 70 passes under the cylinder 66 in contact with the surface thereof, and the warp 10, after leaving the half-drying cylinder 29, passes under said cylinder 66 in contact with said gray, and travels with the latter up, over and partly around the drying cylinder 27 to the guide roll 74, thence rearwardly to the guide roll 30. At the guide roll 30 the gray 70 and the warp 10 separate, the former continuing rearwardly over the guide roll 37, and the latter passing upwardly over the guide roll 32 and then forwardly to a drying cylinder 134. In passing over the cylinder 27 on the gray 70 the warp is dried sufficiently to prevent it from "marking off" or smearing the rolls 74, 30 and 32 which it contacts with on the way to the cylinder 134. The warp is between the rolls 74 and 30 and the gray, as it will be seen must necessarily be the case when it is remembered that the warp and gray turn rearwardly after passing the cylinder 27 with the gray between said cylinder and said warp or on the inside.
- 65 The next step, that of completely drying the warp after it is printed, is taken or effected, so far as this machine is concerned, with the aid of the drying cylinder 134 and another drying cylinder 135 behind said cylinder 134. A frame 136 is provided forward of the frame 1 for the cylinders just men-

tioned. The frame 136 has a bearing 137 for a hollow trunnion 138 at each end of the cylinder 134, and a bearing 139 for a hollow trunnion 140 at each end of the cylinder 135. Live steam enters the cylinder 135 at 141 and exhausts at the opposite end of said cylinder, and live steam enters the cylinder 134 at 142 and exhausts through the opposite end thereof. A guide roll 143 is mounted on a shaft 144 which is journaled in the frame 136 at the back end. A steam-regulator 145 is provided for the live-steam pipes 43, which supply steam to the cylinders 134 and 135, to control the pressure in said cylinders.

The cylinder 134 is driven by means of a sprocket-wheel 147 secured on one of the cylinder trunnions 138, a sprocket-chain 148, and a sprocket-wheel 149 secured to the countershaft 8 above said cylinder. The cylinder 135 is rotated by the warp in passing over the same. The warp 10 passes down over the front of the cylinder 134 and under the same in a rearwardly direction, then up over the cylinder 135 and down behind and under the guide roll 143, thence forwardly beneath said cylinders to the steam-box 14 which it enters at 64. Being thoroughly dried by the cylinders 134 and 135, the warp is ready for the next step or for the treatment in the steam-box 14, which follows.

In taking its tortuous course through the steam-box 14 in contact with the cylinders 22, the warp 10 is subjected both to the heat of said cylinders and the steam in said box, with the result that the color in said warp is set in a most perfect and lasting manner. The steam in the box 14 is at low pressure, while that in the cylinders 22 is at high pressure, and the warp in its course at this time is first dampened or steamed on both sides, and then, upon arriving at the lowermost cylinder 22, is subjected to the heat thereof applied directly to one side of said warp. Next this side of said warp is exposed to the steam in the box and the other side is brought into contact with the second cylinder 22 in the direction taken by the warp, and these alternate double exposures occur until the warp leaves the uppermost cylinder 22 and passes out of the box through the opening 65, the last exposure in said box being to the steam therein on both sides of the warp. Upon emerging from the front of the steam-box 14, the warp passes forward to the drying cylinder 21. While in contact with the cylinder 21 the warp 10 is thoroughly, completely and finally dried, the steam which was taken up thereby in said box being entirely driven off. It is by this means and in this manner that not only is the required setting of the color produced, but also the final drying which obviates any liability to mildew on the part of

the warp after being wound on the loom-beam.

The act of passing over the cylinder 21 to be dried constitutes a step that is supplementary to the act of passing through the steam-box 14, and might be considered as a part of the color-setting or -fixing step. The warp 10 travels rearwardly and forwardly under and with the cylinder 21, after passing over the upper and front portions thereof, and upon leaving said cylinder passes to the guide roll 24 and over the same. From the roll 25 the warp 10 in this case drops to a measuring-roll 150 at the rear end of a section of the machine which comprises a number of other elements besides said measuring-roll, a loom-beam, 151 at the front of the machine and of said section being included among such elements. The elements at the front end of the machine are supported by a frame 152, and may be said to include, besides the measuring-roll 150 and the loom-beam 151, a second measuring-roll 153, two splitting-rods 154, an expansion-comb 155, and draft rolls 156, 157 and 158. Each of the measuring-rolls 150 and 153 has a shaft 159 which is journaled in bearings 160 on the frame 152. The splitting-rods 154 are supported in holders 161 mounted on brackets attached to the sides of the frame 152, one of such brackets appearing at 162. The second-measuring-roll is in front of the first, the splitting-rods are ahead of said second roll and arranged one forward of the other. Next is the expansion-comb 155 which is mounted at each end in a support 163 on the frame 152. In front of each support 163 is a bearing 164 for one end of a shaft 165 upon which the roll 156 is mounted. The roll 157 is mounted below the roll 156 on a shaft 166 which is journaled in the frame 152, and the roll 158 is mounted on a shaft 167 which also has its bearings in said frame. The roll 158 is at the front end of the frame 152, and is in contact with the roll 157, as also is the roll 156, in the absence of the warp 10. The warp-beam 151 is in front of the roll 157 and below the roll 158. The warp-beam has suitable axial supports, one of which appears at 168 and is journaled in a forwardly-extending bearing bracket 169 at the front end of the frame 152 on one side. The axial support 168 is a friction member which is capable of revolving the warp-beam 151, and such support has a gear 170 secured thereon. A shaft 171 is journaled in the frame 152 below the shaft 166, and carries at one terminal a sprocket-wheel 172 and at the other terminal a pinion 173. A sprocket-chain 174 drives the sprocket-wheel 172, the shaft 170 and the pinion 173 from a sprocket-wheel, on the foremost counter-shaft 8, similar to the sprocket-wheel that is shown thereon at 7. There is a gear 175 which is secured on the

shaft 166 and is in mesh with the pinion 173 and with the gear 170. Thus the roll 157 and the friction member 168 for the warp-beam 151 are driven positively, while 5 the rolls 156 and 158 are actuated by reason of their contact with said roll 157, or by the warp 10 in traveling over said rolls 156 and 158, aided by said roll 157. The measuring-rolls are actuated by the moving warp. The 10 warp-beam is not driven positively by the friction member 168.

The warp 10 travels, in a forwardly direction, under the measuring-roll 150, over the measuring-roll 153, above and below the 15 splitting-rods 154, that is to say, the warp-units pass above and below said rods, through the expansion-comb 155, over the roll 156, partly around the roll 157, and over the roll 158 to the warp-beam 151, upon 20 which latter the now finished warp is finally wound. From this point the warp on the warp-beam 151 is taken to a frame wherein said beam is mounted and said warp is drawn into the harnesses and reed for weaving. The roll 150 measures the number of 25 yards of the printed warp which pass in contact therewith, and the roll 153 measures and marks the lengths of the cuts or pieces, all in the usual and well-known manner.

30 The splitting-rods 154 separate the warp-units, which up to this time have been stuck together in a more or less continuous or unbroken strip or web, so as to prepare them for the subsequent weaving operation for 35 which they are intended. It is here that the weaver's lease is taken and transferred to place between the expansion-comb 155 and the draft roll 156. These operations and their purpose are so well known that no 40 explanation is here needed.

A crank 176 is provided for the expansion-comb 155. The purpose of the expansion-comb is to fit as it were the warp-units to the loom-beam, or, in other words, to distribute 45 properly said warp-units on said beam and compensate for any difference that may exist between the combined width of

said units behind said comb and the width or length of said beam.

The object of the draft rolls is obvious, 50 and it need only be observed in connection therewith that said rolls are driven in exact time with the rest of the machine, so as to prevent any undue strain from being put upon the printed warp-units. 55

With the aid of this machine the method can be put into practise in an expeditious and economical manner, there being one continuous operation, and the most satisfactory results are obtained in the perfect warp 60 turned out. The moving parts being driven and timed as they are there need be practically no stops on account of broken warp.

It should be stated more clearly, perhaps, than has been done hereinbefore, that the 65 adhesive material and the half-drying cylinder prepare the warp for printing by first sticking the warp-units together and then drying one side—the side that is to receive the color. It would be impracticable to attempt 70 to print on loose warp, or on warp that was either dry throughout or moist throughout, as will readily be understood.

What I claim as my invention, and desire to secure by Letters Patent, is— 75

1. A method, of printing warp, consisting in causing a plurality of warp-units arranged side by side to adhere to each other, in completely drying such units, so arranged and treated, on one side only, and in applying 80 printing or coloring material to the dry side thereof.

2. A method, of printing warp, consisting in causing a plurality of warp-units arranged side by side to adhere to each other, 85 in completely drying such units, so arranged and treated, on one side only, in applying printing or coloring material to the dry side thereof, and in treating such units to set the color therein.
